UNITED STATES PATENT OFFICE.

JOSEPH L. McWILLIAMS AND JOSEPH MAROSKY, OF SAN FRANCISCO, CALIFORNIA.

FLOOR-LAYING DEVICE.

Application filed March 26, 1927. Serial No. 178,779.

This invention relates to improvements in floor laying devices, and has particular reference to a device which when laid upon a concrete floor will serve to support a plurality of parallel molds in which sleepers may be cast.

The principal object of this invention is to provide means whereby sleepers may be cast, all of which sleepers will have a top surface which is level, thereby permitting a floor to be laid upon the same.

Another object is to provide sleepers which will present a one hundred per cent bearing surface in counter-distinction to the customary wooden sleepers ordinarily laid upon a concrete floor, which wooden sleepers have to be shimmed in the low places.

Another object is to provide a device of this character which may be readily collapsed for the purpose of transporting the same from place to place.

A further object is to provide a device which is capable of unit expansion thereby permitting the device to be employed upon floors of varying area.

Other objects and advantages will be apparent during the course of the following description.

In the accompanying drawing forming a part of this specification and in which like numerals are employed to designate like parts throughout the same,

Figure I is a top plan view of our device as the same would appear when laid upon a concrete floor of a room,

Figure II is a side elevation of our device,

Figure III is a side elevation of one of the straight edge supporting members,

Figure IV is a top plan view of Figure III, and

Figure V is a detail view on an enlarged scale of one of the hangers.

In laying a wooden floor over a concrete floor, it has been common to lay parallel spaced wooden sleepers upon the concrete surface and due to the fact that the concrete floor was seldom level, the result was that there were high spots in some places and low spots in others.

It has therefore been necessary to place shims or wedges beneath the sleepers with the result that when the wooden floor was laid upon the sleepers and nailed thereto, the act of hammering often caused the shims to

become misplaced, resulting in a sprung floor, and where the floor was of considerable area, the same often had waves therein.

In order to overcome these difficulties we have constructed a device for supporting a plurality of parallel molds, the upper edge of each of said molds, being on the same plane with the result that when a plastic composition is poured within the molds a smooth, even with the top of the molds and perfectly level set of sleepers will be formed. At the same time, the plastic composition will contact the concrete flooring thus resulting in a one hundred per cent bearing throughout the entire length of the sleeper.

In the accompanying drawings, wherein for the purpose of illustration is shown a preferred embodiment of our invention, the numerals 5 and 6 designate the side walls of a room and the numeral 7 the end wall thereof, while the numeral 8 refers to a concrete floor laid within the room. The contour of this floor is best illustrated in Figure II; the unevenness of the floor however, being somewhat exaggerated so as to better illustrate our invention.

We employ a plurality of jacks 9 which are provided with tripod legs 11. Each of these jacks has a threaded member 12 having a knurled hand wheel 13 upon its upper extremity. A lock nut is shown at 14 while a straight edge lock 16 is threadedly supported upon the screw-threaded member 12.

In using our device, a plurality of these jacks are positioned within the room as best illustrated in Figure I. These jacks serve to support straight edges which may be single pieces or constructed in sections. Two of these straight edges are shown in Figure I and designated by the numerals 17 and 18.

When a continuous straight edge is employed, the same passes through a slot 19 formed in the straight edge block 16. When several sections are employed, the ends are supported in notches 21 (see Figures III and IV).

After the straight edges have been set up and leveled, the molds are hung thereon, which molds consist of parallel spaced angle irons as designated at 22 and 23. These angle irons are spaced from each other by spacers 24 and 26 which are preferably tubular members through which a bolt 27 passes.

At 28, we have shown hangers, which hangers are adapted to hook over the top

of the straight edge and to engage the end of the bolt 27 (see Figure V).

The result of this construction is that assuming that all of the hangers are of uniform length, all of the molds will be level with each other as illustrated in Figure II.

In order to maintain the mold in proper spaced relation with the next adjacent molds, spreaders are employed, which preferably consist of strap iron members 29 which lap upon each other and are fastened together by a bolt 31.

Suitable perforations are provided in these members 29 so that the distance between the molds may be adjusted to suit conditions.

At A in Figure II, we have shown one of the molds filled with a plastic composition which illustrates the method of employing our device.

It will be obvious that if all of the molds were filled with plastic composition, the resulting sleepers would be level with each other.

It will thus be seen that we have provided a very simple device which will accomplish all the objects herein set forth in an efficient manner.

It is to be understood that the form of our invention herewith shown and described is to be taken as a preferred example of the same, and that various changes relative to

the shape, size, material, and arrangement of parts may be resorted to without departing from the spirit of the invention or the scope of the subjoined claims.

Having thus described our invention, we claim:

1. In a floor laying device, a plurality of jacks spaced one from the other, a straight edge supporting member mounted on each of said jacks, means for elevating said supporting members, a straight edge extending between said jacks and carried in said supporting members, means for suspending parallel spaced molds from said straight edge.

2. In a device of the character described, a pair of parallel spaced straight edges, means for leveling said straight edges, a plurality of molds suspended from said straight edges and means for spacing said molds from each other.

3. In a device of the character described, a pair of parallel spaced straight edges, threaded members adapted to support said straight edges in a level plane, spaced mold members suspended from said straight edges and extending between said straight edges, and means for maintaining said mold members in spaced relation with each other.

In testimony whereof we affix our signatures.

JOSEPH L. McWILLIAMS.
JOSEPH MAROSKY.
